UNITED STATES PATENT OFFICE.

WILLIAM F. BROWN, OF WOMBLE, ARKANSAS.

SAW-SHARPENER.

1,145,746.

Specification of Letters Patent.

Patented July 6, 1915.

Application filed October 11, 1912. Serial No. 725,265.

To all whom it may concern:

Be it known that I, WILLIAM F. BROWN, a citizen of the United States, residing at Womble, in the county of Montgomery and 5 State of Arkansas, have invented new and useful Improvements in Saw-Sharpener, of which the following is a specification.

The present invention relates to a saw sharpener or gummer, and resides in the 10 novel construction, combination and operative arrangement of parts set forth in the following description, and falling within the scope of the appended claim.

In the drawings which accompany this 15 specification, and which form a part thereof there has been illustrated a satisfactory reduction of the device to practice, but it is to be understood that the showing therein is merely illustrative, and that the device is 20 susceptible to such changes in material, size, proportion and details of construction as will fall within the scope of the appended claim.

In the said drawings, Figure 1 is a perspective view of a device constructed in accordance with the present invention. Fig. 2 is a central longitudinal sectional view through the same and the mandrel turned at right angle to the stand from its position 25 shown in Fig. 1. Fig. 3 is a transverse sectional view taken approximately upon the line X—X of Fig. 1.

My device is adapted to be erected upon the filing bench where the saw is finished, and 30 the frame thereof is preferably constructed of pipe sections and connections, whereby the same may be taken down, and packed for storage or transportation at a minimum amount of time and labor, and also whereby 35 the same may be easily set up when desired.

Furthermore it is my purpose to construct a machine whereby various sizes of saws may be gummed, and whereby any desired pitch or bevel will be imparted to 40 the teeth of the saw so that saws for various purposes, such as saws for "cut offs" "rip saws" or "edger" saws may be readily sharpened and gummed.

In the device illustrated by the drawings, 45 the numeral 1 designates a filing bench, and 2 the frame of my improvement which is mounted upon the bench. This frame is 50 preferably constructed of a plurality of pipe sections or rods, and comprises side members 3 and 4, each of the same being of a similar construction, and each embodying

a pair of spaced uprights 5 having their lower extremities offset to provide feet 6, and their upper extremities provided with removable couplings 7.

The numerals 8 designate the connecting members for the up-rights which are removably secured to the couplings. The connecting members 8 are centrally provided with in-turned bearings 9, that includes a 55 detachable bushing 9' which can be renewed when worn out, for the reception of a shaft 10. The bearing members 8 have also connected therewith a substantially rectangular frame 11, the same being preferably constructed of pipe members and couplings therefor, and the said frame is pivotally secured to the bearings 9. The frame 11 is provided with a rearwardly extending member or arm 12 upon which is arranged a 60 weight 13. The weight 13 is slideable upon the arm 12, and is sustained in an adjusted position upon the said arm through the medium of a thumb screw 14. The forward end of the frame 11 has connected 65 thereto a substantially U-shaped member 15, the said member being also preferably formed of pipe sections, and couplings for the sections. The longitudinal arms of the U-shaped member 15 have their extremities 70 provided with couplings forming bearing 16, and arranged for rotation within the said bearings is a second shaft 17. The shaft extends a suitable distance through the oppositely arranged bearing 16 and has 75 one of its ends provided with a fly wheel 18, while the opposite projecting end has secured thereto a saw filing and gumming member which is in the nature of an emery wheel 19. Secured upon the shaft 17 between the longitudinal arms of the U-shaped 80 member 15 is a belt wheel 20, the said wheel being arranged forward of a similar belt wheel 21 which is connected with the shaft 10, while the numeral 22 designates an end- 85 less belt for the said wheels. The shaft 10, which may be termed the power shaft of the device, is further provided with a second belt wheel 23, and the numeral 24 designates the belt which acts upon the said wheel 23 90 and which in turn is connected with any suitable source of power (not shown). Secured to the couplings forming the bearing 16 are the arms of a substantially U-shaped handle 25, the same being disposed conveniently to the operator, so that the pivoted frame, and emery wheel may be brought to 95 100 105 110

a desired angle to permit of the emery wheel properly acting upon the teeth of the saw.

Arranged upon the upright 5 of the frame adjacent the wheel 19 is a collar 26, the said collar being sustained in an adjusted position upon the said upright through the medium of a binding screw 27.

The numeral 28 designates a member or arm which is secured to the collar 26, and the said arm has its outer extremity enlarged. The enlarged portion of the arm is provided with a vertically arranged threaded opening which is adapted for the reception of a threaded member 29, and the said member 29 may be, and preferably is sustained against rotation through the medium of a binding screw 30. The upper extremity of the member 29 has connected thereto a saw mandrel 31. This mandrel 31 is preferably rotatably secured upon the screw 29, but is also normally sustained against rotation through the medium of a binding element, in the form of a bolt 32 which passes through a suitable threaded opening in the mandrel and which contacts with the upper extremity of the threaded member 29.

The mandrel has its outer face provided with a cam lever 33 whereby a saw 34 is clamped upon the mandrel after the said saw has its central opening passed over the cam lever and upon the mandrel.

From the above description taken in con-

nexion with the accompanying drawings it will be noted that the mandrel may be adjusted vertically of the frame 2 to sustain the saw in a proper position to be operated upon by the filing wheel 19; that the saw may be inclined to permit of the wheel 19 imparting a desired bevel to the teeth; that the threaded member 29 affords a minute adjustment of the saw and mandrel, after the arm 28 has been adjusted and sustained upon the upright of the frame 2; also that the wheel 19 is removable so that other sharpening wheels of varying thicknesses and diameters may be arranged upon the shaft 17, and from the above it is thought that the advantages and operation of the device will be perfectly apparent without further detailed description.

Having thus described the invention, what I claim is:—

In a device of the class described, in combination with a support, a swinging frame, bushings having screw threaded engagement with said swinging frame and said support, a shaft journaled in said bushings on which said frame swings.

In testimony whereof I affix my signature in presence of two witnesses.

WILLIAM F. BROWN.
